UNITED STATES PATENT OFFICE.

NATHAN M. LOWER, OF SCHENECTADY, NEW YORK.

LOCOMOTIVE-TENDER.

1,219,334.

Specification of Letters Patent. Patented Mar. 13, 1917.

Application filed January 18, 1916. Serial No. 72,692.

To all whom it may concern:

Be it known that I, NATHAN M. LOWER, a citizen of the United States, and resident of Schenectady, county of Schenectady, and 5 State of New York, have invented certain new and useful Improvements in Locomotive-Tenders, of which the following is a specification and which are illustrated in the accompanying drawings, forming a part 10 thereof.

The invention relates particularly to that type of locomotive tenders in which, in addition to a fuel bin at the forward end of the tender, there is provided a fuel deck on 15 top of the water tank, and back of the slope sheet forming the rear wall of the bin.

The object of the invention is to provide power means in tenders of this type for moving the fuel forwardly on the deck to 20 the slope sheet, down which it may be moved by gravity, or, if necessary, by pusher mechanism of some approved form.

Further objects of the invention are to provide locomotive tenders with a coal- 25 pushing motor which will be compact in form, well protected from injury by fuel as the latter is loaded onto the tender, and which shall be so controlled that normally it will not be under the influence of fluid 30 pressure.

The invention consists in a structure such as is hereinafter described, and as illustrated in the accompanying drawings, in which

35 Figure 1 is a detail vertical longitudinal section of the tender, partly in elevation;

Fig. 2 is a similar detail showing the motor in section and drawn to a larger scale;

Fig. 3 is a detail plan view of the tender;

40 Fig. 4 is a longitudinal central section of the motor controlling valve;

Fig. 5 is a plan view partly in section, of the valve mechanism,

Fig. 6 is an end elevation of the same,

45 Fig. 7 is a view similar to Fig. 2, the cylinder being retracted,

Fig. 8 is a detail transverse vertical section through the tender deck, showing the motor in end elevation,

50 Fig. 9 is a detail transverse vertical section on the line 9—9 of Fig. 7,

Fig. 10 is a rear elevation of the motor,

Fig. 11 is a detail longitudinal central vertical section of the tender showing a 55 modified form of construction,

Fig. 12 is a detail plan view of the device as shown in Fig. 11.

The body of the tender is provided with side walls 10, 11, and a water tank 12. The slope sheet 13, forming the rear wall of the 60 fuel bin, extends at its lower end well forward in the tender. The side walls 10, 11, of the tender extend a considerable distance above the top plate 14 of the tank 12, and at or near the rearward end of the tank 65 there is a vertical transverse wall 15, thereby affording substantial fuel-carrying space on top of the tank.

In tenders of this type it has been necessary for the locomotive fireman, after 70 emptying the fuel bin proper, to shovel the coal on the top of the tank down into the bin to bring it within his reach in stoking the furnace. This not only materially increases the already laborious hand-firing operation, but may interrupt the feeding of the furnace at a critical time when it is necessary to keep the fire-box well supplied with fuel.

In addition to the parts of the tender already described, all of which are old, the improved tender is provided with a motor, generally designated by the numeral 16, located upon and secured to the top plate 14 of the tank, and suitable fuel pushers actuated by this motor for advancing the fuel on the deck over the tank to the slope sheet 13, down which it may slide by gravity or 80 may be pushed by suitable mechanical appliances.

90 While the motor 16 may be of any suitable type, there is here shown as a preferred form a reciprocating motor comprising a stationary piston 17, rigidly secured by means of a tubular shaft 18 to a back plate 95 19, secured to the plate 14; and a reciprocating cylinder 20 inclosing the piston and sliding upon the shaft 18, its rearward end being provided with a suitable stuffing box 21, the cylinder also resting upon a guideway 22 projecting forwardly from the plate 19. A tube 23, located within the shaft 18, is secured at one end to the piston 17, and at the other end in a plug 24 fitted within the rearward end of the shaft 18.

100 While the construction described provides a simple and cheap arrangement for leading steam to and from the piston, any other which accomplishes this purpose may be substituted; it being important only that 105 there be two independent ducts leading to the piston.

110 Steam and exhaust pipes 25, 26, are connected, respectively, with the rear ends of

the tubular shaft 18, and the tube 23, and are preferably led thereto through a conduit 27 extending vertically through the tank 12. Lateral ports 28, 29, bring the two piston stem ducts into communication with the cylinder chamber, opening, respectively, back and forward of the piston 17. The piston is provided with a central cavity, and hence in cross-section is substantially U-shaped. The front head 30 of the cylinder is provided with a central instanding boss 31 to receive the chamber in the face of the piston, and the rear head 32 of the cylinder is provided with a central cavity 33 to receive the central enlargement 34 of the piston.

The boss 31 makes a substantially close fit with the piston cavity, and the enlargement 34 of the piston makes a similar fit with the cavity 33, thereby providing for the cushioning of the motor at the end of each stroke. The ports 28 and 29 lead, respectively, from the tubes 18 and 23 through the rear and front faces of the piston 17, thereby providing for the complete exhaust of the steam from the chamber 33 and the annular chamber surrounding the boss 31, and for supplying steam to these chambers for the commencement of the next stroke.

The pipes 25, 26, lead forwardly under the tank 12 and upwardly through a conduit 35 through the forward end of the tank 12 to a controlling and manually operated valve located within convenient reach of the fireman when in the engine cab, and generally designated in Figs. 1 and 3 by the numeral 36. This valve constitutes a further improvement in locomotive tenders, and is applicable as well to the tender forming the subject of this specification as to tenders of other types provided with power-actuated coal pushers. The load imposed upon the motor when the tender is carrying the full supply of fuel is excessive, and is apt to temporarily stall the motor. When under such circumstances power pressure is continued on the motor, there is apt to occur a sudden forward impulse when the load is partially relieved, with danger of injuring the operator. To avoid this difficulty provision is made for the automatic return of the valve to central position when released by the operator, and when in this position pressure is equalized in both ends of the cylinder preferably by cutting off the steam and opening both of the pipes 25, 26, to the atmosphere.

A desirable and operative form of valve for performing this function is shown, and comprises a cylindrical casing 37, having nipples 38, 39, adjacent each end to which are attached, respectively, the pipes 25, 26; a central nipple 40, to which a steam pipe 41 is attached; and an end nipple 42 to

which the exhaust pipe 43 is connected. The cylinder is preferably provided with a lining 44, ported for communication with the nipples 38, 39, through circumferential chambers 45, 46, formed within the wall of the valve casing, and also for communication with the steam nipple 40.

A tubular valve 47, open at each end, reciprocates within the lining 44, and is contracted or reduced in diameter intermediate of its ends to provide an annular chamber 48 which is in constant communication with the steam nipple. The length of the valve is such that when in central position both of the annular chambers 45, 46, 80 are uncovered to the nipples 38, 39. Both ends of the valve being open, the nipples 38, 39, are thus both in communication with the exhaust nipple 42 when the valve is centered, and consequently steam is exhausted from 85 both ends of the motor cylinder 20.

The valve 47 is automatically centered by springs 49, 50, reacting between its ends and the ends of the casing 37. The valve is provided with a stem 51, leading through the head 52 which closes the end of the cylinder 37 opposite the exhaust nipple, a suitable stuffing box being provided. The valve is controlled by a handle 53, pivoted to a bracket 54, here shown as extending from the head 52, the handle being connected to the stem 51 by means of links 55, 56, and a pin 57. The shifting of the valve 47 in either direction from the central position will open communication from the steam pipe to one of the pipes 25, 26, leaving the other in communication with the exhaust pipe, and upon the release of the handle 53 the valve is automatically centered, thereby not only stopping the motor but opening 105 both ends of its cylinder to the exhaust.

Suitable fuel pushers are associated with the motor, and as shown consist of a pair of heads 57^a, 58, projecting laterally from the head of the cylinder 20, and, if desired, 110 cast integrally therewith, as plainly shown in Fig. 8, each of these heads being provided with a sloping back, as shown at 59, in order that upon the backward stroke of the motor it may easily slide under the mass of 115 fuel. A similarly shaped head 60 extends forwardly from the heads 57^a, 58, and is shown as being hinged thereto. These fuel-engaging elements may, however, take various forms; and the same is true of other 120 details of the device.

In service the operator may give the motor a full forward stroke, in which case all of the fuel immediately in front of the head 60 will be pushed forward to the top 125 of the slope sheet, and the fuel in front of the heads 57^a, 58, will be advanced to a position to be engaged by the head 60 on its next advance stroke. The motor may then be given a complete reverse stroke, 130

moving the several heads backwardly under the mass of fuel. Or the operator may give the motor a succession of partial advance strokes, thus throwing down only so much fuel as will meet his immediate requirements. After each of these partial strokes the valve will be centered to open both ends of the cylinder to the exhaust, bringing it to rest and preventing any 10 tendency to a movement in either direction due to a diminution of the load by reason of the shifting of the fuel.

In Figs. 11 and 12 is shown a different form of construction, in which the coal pusher mechanism is applied to the slope sheet 13 of the fuel bin and comprises a motor 16 of the same form as the motor shown in Figs. 1, 2 and 3. A plate 61 is preferably secured to the slope sheet 13, and 20 extends along the flat bottom 62 of the fuel bin, the motor 16 being mounted upon this plate and located at the upper end of the slope sheet. The motor is provided with pusher heads 57^a, 58 and 60, shown as of 25 the same form as those of the construction already described, the forward pusher head traveling forwardly over the flat bottom of the fuel bin.

In devices of the general character of 30 that shown in Figs. 11 and 12, as heretofore made, it has been found necessary to locate the motor practically entirely above the water tank, and as a consequence it has been in the way of the spout used in filling 35 the tank. The form of motor here shown may be applied as illustrated, so that it does not extend above the coal bin.

I claim as my invention—

1. In a locomotive tender having a fuel 40 bin, in combination, a fuel deck back of the bin, and fuel advancing means for moving the fuel from the deck to the bin.

2. In a locomotive tender having a fuel 45 bin, in combination, a fuel deck back of the bin, a fuel pusher reciprocable over the deck, and a motor for actuating the pusher.

3. In a locomotive tender having a fuel 50 bin, in combination, a fuel deck back of the bin, a fuel pusher reciprocable over the deck, and a motor located on the deck for actuating the pusher.

4. In a locomotive tender having a fuel 55 bin, in combination, a fuel deck back of the bin, a fuel pusher reciprocable over the deck, and a motor for actuating the pusher, such motor comprising a stationary piston and a reciprocating cylinder.

5. In a locomotive tender having a fuel 60 bin, in combination, a fuel deck back of the bin, a motor located on the deck and comprising a piston and cylinder, one thereof being reciprocable, and pushers connected with the reciprocable member for advancing fuel over the deck toward the bin.

6. In a locomotive tender having a fuel

bin, in combination, a fuel deck back of the bin, a motor located on the deck and comprising a piston and cylinder, one thereof being reciprocable, the reciprocable member having lateral extensions for pushing 75 the fuel over the deck toward the bin.

7. In a locomotive tender having a fuel bin, in combination, a fuel deck back of the bin, a motor located on the deck and comprising a stationary piston, and a reciprocable cylinder, the cylinder head being laterally extended to provide pushers for 75 advancing fuel over the deck.

8. In a locomotive tender having a fuel bin, in combination, a fuel deck back of the 80 bin, a motor located on the deck and comprising a piston and cylinder, one thereof being reciprocable, and pushers connected with the reciprocable member, and a pusher forward of and attached to the first-named 85 pushers, for advancing the fuel over the deck.

9. In a locomotive tender having a fuel bin, in combination, a fuel deck back of the bin, a motor located on the deck and comprising a piston and cylinder, one thereof being reciprocable, the reciprocable member having lateral extensions, and a pusher 90 forward of and attached to such extensions, the pusher and extensions being adapted to 95 advance fuel over the deck.

10. In a locomotive tender having a fuel bin, in combination, a fuel deck back of the bin, a motor located on the deck and comprising a stationary piston, and a reciprocable cylinder, the cylinder head being laterally extended to provide pushers for 100 advancing fuel over the deck, and a pusher forward of and attached to the extensions.

11. In a locomotive tender having a fuel 105 supporting floor, fuel pushing means reciprocable over the floor, a reciprocable fluid motor for actuating the pushing means, and means for controlling such motor and adapted normally to provide equal pressure 110 on both faces of its piston.

12. In a locomotive tender having a fuel supporting floor, fuel pushing means reciprocable over the floor, a reciprocable fluid motor for actuating the pushing 115 means, such motor being provided with a controlling valve adapted to normally maintain a balanced pressure on both faces of the motor piston.

13. In a locomotive tender having a fuel 120 supporting floor, fuel pushing means reciprocable over the floor, a reciprocable fluid motor for actuating the pushing means, such motor being provided with a controlling valve, such valve being ported to connect the two ends of the motor cylinder with a pressure and an exhaust pipe in alternation when in its extreme positions and to connect both ends of the cylinder with the exhaust when in its central position. 130

14. In a locomotive tender having a fuel supporting floor, fuel pushing means reciprocable over the floor, a reciprocable fluid motor for actuating the pushing means, such motor being provided with a controlling valve, such valve being ported to connect the two ends of the motor cylinder with a pressure and an exhaust pipe in alternation when in its extreme positions and to connect both ends of the cylinder with the exhaust when in its central position, and means for returning the valve to and maintaining it at central position.
15. In a locomotive tender having a fuel supporting floor, fuel pushing means reciprocable over the floor, a reciprocable fluid motor for actuating the pushing means, a valve for controlling the motor, such valve comprising a cylindrical casing having a lateral port adjacent to each of its ends and communicating with the motor, a pressure port intermediate of such two ports and an exhaust port in one of its ends, and a tubular valve reciprocable in the casing, such valve having a cavity in its outer wall intermediate of its ends adapted to constantly register with the pressure port, the valve being arranged to alternately bring the first two ports into communication with the pressure and exhaust ports, and means for automatically centering the valve.
16. In a locomotive tender having a fuel supporting floor, fuel pushing means reciprocable over the floor, a reciprocable fluid motor for actuating the pushing means, a valve for controlling the motor, such valve comprising a cylindrical casing having a lateral port adjacent to each of its ends and communicating with the motor, a pressure port intermediate of such two ports and an exhaust port in one of its ends, and a tubu-

lar valve reciprocable in the casing, the first two ports being uncovered when the valve is in central position; the valve having a lateral cavity in constant communication with the pressure port and being adapted to register with either of the first-named ports, and means for automatically centering the valve.

17. In a locomotive tender having a fuel supporting floor, fuel pushing means reciprocable over the floor, a reciprocable fluid motor for actuating the pushing means, a valve for controlling the motor, such valve comprising a cylindrical casing having a lateral port adjacent to each of its ends and communicating with the motor, a pressure port intermediate of such two ports and an exhaust port in one of its ends, and a tubular valve reciprocable in the casing, the first two ports being uncovered when the valve is in central position, the valve having a lateral cavity in constant communication with the pressure port and being adapted to register with either of the first-named ports, and balanced spirals reacting between the ends of the valve and abutments in the casing.

18. In a locomotive tender, in combination, a fuel supporting floor, a reciprocable motor mounted thereon and having a stationary piston and a movable cylinder, the piston having a central dome and the piston heads being of complementary form to receive such dome, and fuel pushers extending laterally from the cylinder.

19. In combination, a locomotive tender adapted to carry fuel, a motor comprising a stationary piston and a reciprocable cylinder, and fuel-advancing means attached to the cylinder.

NATHAN M. LOWER.
